Primary Examiner — Karen S Acker*(74) Attorney, Agent, or Firm* — Bachman & LaPointe, P.C.**CLAIM**

The ornamental design for a flexible sheet material, as shown and described.

DESCRIPTION

FIG. 1 is a perspective view of a first embodiment of a flexible sheet material in accordance with the present invention. The figure is an enlarged detail of FIG. 2;

FIG. 2 is a perspective view of the design of FIG. 1 shown as part of a roll;

FIG. 3 is a perspective view of a second embodiment of a flexible sheet material in accordance with the present invention. The figure is an enlarged detail of FIG. 4; and,

FIG. 4 is a perspective view of the design of FIG. 3 shown as part of a roll.

The partially removed tape shown in FIGS. 2 and 4 represents unclaimed environmental subject matter included to show the design in a position of use.
